(No Model.)

A. RIGNY.

BOTTLING DEVICE.

No. 289,714.

Patented Dec. 4, 1883.

UNITED STATES PATENT OFFICE.

ALFRED RIGNY, OF NEW YORK, N. Y.

BOTTLING DEVICE.

SPECIFICATION forming part of Letters Patent No. 289,714, dated December 4, 1883.

Application filed June 20, 1883. (No model.)

To all whom it may concern:

Be it known that I, ALFRED RIGNY, of the city, county, and State of New York, have invented certain new and useful Improvements 5 in Bottling Devices, of which the following is a full, clear, and exact description.

Reference is to be had to the accompanying drawings, forming part of this specification, in which similar letters of reference indicate corresponding parts in all the figures.

Figure 1 is a sectional side elevation of my improvement shown as applied to a bottle. Fig. 2 is a side elevation of the lower part of 15 the same. Fig. 3 is a sectional plan view of the same, taken through the line $x-x$, Fig. 2.

The object of this invention is to facilitate the bottling of liquids, and prevent waste of the liquids while being bottled.

A represents a tube of such a size that it 20 can be readily inserted in the bottles to be filled, and of such a length that when inserted in a bottle it will occupy the exact space required to be left empty for corking the said bottle. The upper end of the tube A is 25 screwed into the open lower end of a short hollow cylinder, B, into an opening in the upper part of the side of which is screwed a nozzle, C, to receive the end of a rubber pipe leading to the cask from which the liquid is 30 to be drawn. The lower end of the tube A is closed by a valve, D, made of rubber or other suitable material, and attached to the lower end of a rod, E, to which it is secured by nuts 35 screwed upon the said rod, above and below the said valve. When the valve D is made of rubber, it should be stiffened by a metallic backing or seat, F, attached to the rod E. The valve D is centered upon the lower end of the tube A by two or more springs, G, secured to 40 the rod E at the inner side of the said valve D, and which rest and slide against the inner surface of the said tube A. The rod E passes out through a stuffing-box in the upper end of

the cylinder B, and upon its upper part is placed a spiral spring, H, the lower end of 45 which rests upon the upper end of the said cylinder B. The upper end of the spring H rests against a disk, I, placed loose upon the upper part of the rod E, and secured in place by the neck of the knob J, screwed upon the 50 end of the rod E. The spring H is covered and protected by a tubular casing, K, screwed upon the rabbed upper end of the cylinder B. The upper end of the casing K is closed by a cap, L, screwed upon it, and which has 55 a hole through its center for the passage of the neck of the knob J. The neck of the knob J is made of such a length as will allow the rod E to have sufficient downward movement to fully open the valve D.

In using the implement the tube A is inserted in the bottle to be filled, and the nozzle C is connected with the cask from which the liquid is to be drawn by a rubber pipe. The knob J is then pressed downward, which opens 65 the valve D and allows the liquid to flow into the said bottle. When the bottle is full, the knob J is released, and the valve D is instantly closed by the spring H, so that the implement can be moved from one bottle to another 70 without any waste of liquid.

Having thus described my invention, what I claim as new, and desire to secure by Letters Patent, is—

The combination of the tube A, open at 75 both ends, the separate cylinder B, secured to the upper end thereof and carrying a lateral supply-pipe, the centered rod E, carrying at its lower end the valve D, and the spring H, arranged in a case above the cylinder B, as 80 shown and described.

ALFRED RIGNY.
